CLAIM

Sep. 5, 2019 (EM) 006816773-0008

The ornamental design for a media player device with light, as shown and described.

(51) **LOC (14) Cl.** **14-01**

DESCRIPTION

(52) **U.S. Cl.**

FIG. 1 is a top-front perspective view of the media player device with light, with an ambient light turned off;

USPC **D14/496; D14/214**

FIG. 2 is a top-front perspective view thereof, with the ambient light turned on, as shown by the dashed lines;

(58) **Field of Classification Search**

FIG. 3 is top-right perspective view thereof, with the ambient light turned off;

USPC D14/167, 168, 170–172, 188, 193–198,

FIG. 4 is an alternate top-right perspective view thereof, with the ambient light turned on, as shown by the dashed lines;

D14/203.1–203.8, 204, 209.1, 210–217,

FIG. 5 is a rotated right side view thereof, with the ambient light turned off;

D14/219, 221, 222, 224, 239, 496;

FIG. 6 is a top-rear perspective view thereof, with the ambient light turned off; and,

D26/34, 38, 51, 52, 57

FIG. 7 is a different top-rear perspective view thereof, with the ambient light turned off.

CPC B60R 11/0217; G06F 1/1688; G10K 9/22;
